Des. 214,279
Patented May 27, 1969

214,279

LIGHT WRITING TOY

Palmer J. Schoenfield, Evanston, Ill., assignor to Marvin
Glass & Associates, Chicago, Ill., a partnership

Filed June 27, 1968, Ser. No. 12,529

Term of patent 14 years

Int. Cl. D21—02

U.S. Cl. D34—15

Fig 3Fig 4Fig 5Fig 6FIGURE 1 is a perspective view of the light writing toy showing my new design;

FIGURE 2 is a top plan view of the toy, with the writing implement moved to one side of the writing base;

FIGURE 3 is a front elevational view of the toy as seen in FIGURE 2;

FIGURE 4 is a rear elevational view of the toy;

FIGURE 5 is a view taken from the right side in FIGURE 2; and

FIGURE 6 is a view taken from the left side in FIGURE 2.

I claim:

The ornamental design for a light writing toy, substantially as shown.
